W. K. Foster.
Pencil Sharpener.

No 20,262. Patented May 18, 1858.

UNITED STATES PATENT OFFICE.

W. K. FOSTER, OF BANGOR, MAINE.

PENCIL-SHARPENER.

Specification of Letters Patent No. 20,262, dated May 18, 1858.

To all whom it may concern:

Be it known that I, WALTER K. FOSTER, of Bangor, in the county of Penobscot and State of Maine, have invented certain new and useful Improvements in Pencil-Sharpener or Devices for Sharpening or Pointing Pencils or Crayons; and I do hereby declare that the same are fully described and represented in the following specification 10 and the accompanying drawings, of which—

Figure 1, is a side view of a pencil sharpener containing my invention, it being taken so as to exhibit a broadside representation of the handle. Fig. 2, a side view of it 15 showing the handle in edge view and the chip throat. Fig. 3, is a view of it exhibiting the opposite side of it or the light port. Fig. 4, is a vertical and central section taken so as to show the knife or cutter. Fig. 5, is a 20 vertical and central section taken in the opposite direction. Fig. 6, is a transverse section of it, all the figures being made on a scale double that of the usual size of the article.

25 This pencil sharpener is intended to be constructed by casting or founding the body of it in a mold and on the knife or cutter placed and held in the mold.

In the drawings, A, denotes the body of 30 the sharpener as formed with a handle, B, and containing a knife or cutter, C, a conical or tapering chamber, a, and a chip throat, d, the same being arranged together in a manner as shown in the drawings.

35 The upper end of the cutting edge of the knife terminates in a space or chamber, or has a chamber or space, c, formed beyond and against it in the body or upper part of the body A. Furthermore, the said space 40 or chamber is placed between the handle and the blade or cutter, and so that no shavings or particles of the lead while a pencil is being sharpened or pointed can pass into the handle or on the same so as to dirty or 45 soil a person's fingers having hold of the handle. Should the chamber, e, open into the handle or the passage, f, through the same, particles of lead removed from a pencil during the process of pointing it would

50 pass into the space, f, and soil the fingers of the operator. The space, c, and the knife are to be so arranged as to form the pencil or lead thereof with a cylindrical termination to the conical or tapering end, that is, 55 as shown in Fig. 7, wherein, f, denotes the

cylindrical termination and g, the tapering end. In this drawing A, denotes the lead, while B, is the wood of the pencil. The object of so forming the lead with a cylindrical instead of a conical point or end is 60 to enable it subsequently to be reduced to a fine point by rubbing it on paper, sand paper, or a fine file, as artists often prefer to have a pencil so left by the pencil sharpener. Furthermore, that side of the chamber, e, which is opposite to the knife edge, or in other words, the side marked, h, in Fig. 2, is so arranged with respect to the conical chamber, a, as not to touch the lead of the pencil while the same is being sharpened. This prevents any particles of lead 65 from marring or injuring the point or lead. The body A, is also formed with a light port or opening, i, arranged in the opposite side of it to that in which the chip throat is 70 made, such being not only to aid in freeing the chamber, a, of particles of lead and wood, but to enable a person to look through the body and see the lead of the pencil while 75 it is being sharpened or reduced. 80

I claim—

1. Making the pencil sharpener with a space, e, (or its equivalent) so arranged beyond the inner end of the blade C, as to cause the pencil lead to be turned or reduced 85 cylindrically while passing beyond the inner or upper end of the knife.

2. I also claim the arrangement of the space, c, with reference to the handle, that is, so as to be separated therefrom, or not 90 open into the space or opening, f, thereof, the same being for the purpose as set forth.

3. I also claim making the body, A, of the pencil sharpener with a light port or opening, i, arranged opposite to the chip 95 throat, and for the purpose described.

4. I also claim arranging the auxiliary chamber, e, or its side, h, with respect to the conical chamber, a, so that while the lead is being cut by the knife, the lead may not 100 touch the side of the auxiliary chamber or be so near it as to be ground or injured by particles of lead which may adhere to the sides of the auxiliary chamber.

In testimony whereof I have hereunto set 105 my signature.

WALTER K. FOSTER.
